(57) CLAIM

The ornamental design for a retail bottle label, as shown and described.

DESCRIPTION

FIG. 1 is a perspective view of the retail bottle label showing my new design, shown mounted to a bottle illustrated in phantom lines.

FIG. 2 is a right side view of the retail bottle label shown in FIG. 1, the left side view being the same thereof.

FIG. 3 is a front view of the retail bottle label shown in FIG. 1, the rear view being the same thereof.

FIG. 4 is a top view of the retail bottle label shown in FIG. 1; and,

FIG. 5 is a bottom view of the retail bottle label shown in FIG. 1.

The broken line showing of environmental structure is for illustrative purposes only and form no part of the claimed design.
